UNITED STATES PATENT OFFICE.

JAMES D. LALOR, OF BALTIMORE, MARYLAND, ASSIGNOR TO THE LALOR FUEL OIL SYSTEM COMPANY, INC., OF BALTIMORE, MARYLAND, A CORPORATION OF MARYLAND.

LIQUID-FEED SYSTEM.

Application filed April 22, 1925. Serial No. 25,020.

This invention relates to liquid feed systems, more particularly of a kind useful for feeding liquid fuel in light, heating, power or other industrial plants.

5 In a system of the kind with which the present invention is concerned, the liquid fuel is continuously pumped from an underground reservoir usually located outdoors, and passed through more or less elaborately involved housed apparatus comprising, in addition to pumps and necessary auxiliaries such as preheaters, accumulators, filters, strainners, etc., before being delivered to the burners whereby it is consumed in the furnaces. Consequently upon shutting down such a system as at night, or upon failure of the pump for any reason, a considerable amount of liquid fuel is left remaining in the various elements constituting the pumping and "conditioning" equipment within 10 the building.

25 My invention is directed in the main to provisions whereby all the fluid fuel in the indoor apparatus—whether it be in the pump, the component auxiliaries or the connecting piping—is automatically drained back into the supply reservoir when the system is not in use, so that fire hazard is reduced to an absolute minimum.

30 Other objects and attendant advantages will become apparent from the detailed description hereinafter of the typical embodiment of my invention shown in the drawing herewith.

35 With reference to this illustration, 5 indicates the side wall of the building housing the pumping and "conditioning" equipment which is comprehensively designated by the numeral 6. The reservoir 7 constituting the 40 source of fuel supply, is located outdoors and preferably underground at the proper distance from the building to conform to the requirements of insurance underwriters. The fuel is drawn from the reservoir 7 by 45 a pump 8 included in the indoor equipment 6, through a conduit 9, and discharged by the pump into a pipe 10, a by-pass pipe 11 having parallel branches 12 with interposed automatic relief valves 13, being connected 50 to the pipe 10 at 14, serves to conduct any excess delivery of the pump directly back into the reservoir 7 while the system is in operation. The pumped fluid is conveyed by the pipe 10 into the lower end of a pre-heater 15, shown as comprising a vertical 55

cylindric casing that affords a flow passage for the fluid about an internal radiator 16, through which steam or other suitable heating medium is constantly circulated by virtue of connection to supply and return mains 60 17-18. An additional pipe 19 serves to conduct off condensation accumulating in the preheater 15. Interposed in the steam supply main 17 is a standard form of automatic flow regulating valve 20 with a connection 65 21 to a temperature responsive control device 22 located in the flow of fluid within the preheater 15. After traversing the preheater 15, the liquid fuel leaves the top of the same by way of a depending branch pipe 70 23 from a conduit 24. A shunt conduit branch 25 is preferably provided to enable the preheater 15 to be cut out of the system if desired, suitable valves 26 being interposed in the piping to divert the flow as desired. The downward extension 27 of the main 24 delivers the preheated liquid into the bottom of a columnar accumulator 28 through a stand or riser pipe 29 axially within the lower end of the latter. A head 80 of compressed cushioning air is constantly maintained in the top of the accumulator 28 through communication by way of a pipe connection 30 with a suitable compressor, not shown. The oil leaves the accumulator 28 85 through a lateral outlet 31 at the bottom thereof and is conducted by a communicating pipe 32 to the burners or other consuming appliances, (not shown). The flow through the main 32 is controllable by 90 standard hand valves 33 between which is interposed an automatic shut-off valve 34 such as shown and described in Patent 1,103,058, granted me under date of July 14, 1914, this valve being operative to automatically prevent flow of oil to the burners 95 in the event of failure of the pipe lines, or over feeding.

Now it will be noted that when a system of this sort is shut down intentionally, or through failure to function for any reason, a comparatively large amount of oil will remain in the pump 8 and the various afore-described auxiliaries, as well as in the connecting piping,—such condition constituting 100 a very formidable fire hazard. In order to overcome this objection, I provide, in accordance with the present invention, for automatic draining of the system as follows:

105 A common drain conduit 35 is connected 110

by means of vertical branches 36, 37, 38 with the flow conduits 10, 27, 32, at 14, 39, and 40 respectively. At 41 the conduit 35 is in communication with a discharge main 42 which leads directly back into the supply reservoir 7. Check valves 43 are interposed in the conduit 35 at various points to restrict flow to the direction indicated by the dotted arrows, while an automatic drain valve 44 in the discharge main 42 normally prevents flow through the draining system during the operation of the pump. The construction and operation of this valve is fully described in my Patent 1,211,599, granted January 9, 1917. With this arrangement it will be apparent that immediately upon cessation of pump action and consequent automatic opening of the valve 44, the oil remaining in the various parts of the apparatus will immediately begin gravitating back into the reservoir 7, the pump 8, preheater 15 and connections discharging through the branch 36, the accumulator 28 and connections through the branches 37, 38 into the conduit 35, and the latter into the main 42 which leads to the reservoir, the whole operation requiring but a few seconds for its consummation and rendering the entire system completely empty and safe from the standpoint of fire hazard.

Having thus described my invention, I claim:

1. In liquid feed systems of the character described, the combination of pumping and pre-treating apparatus, and means automatically operative to drain all liquid remaining in the system upon cessation of pumping.

2. In liquid feed systems of the character described, the combination of pumping and pre-treating apparatus, a supply reservoir, and means automatically operative to return all liquid remaining in the system upon cessation of pumping to the supply reservoir.

3. In liquid feed systems of the character described, the combination of pumping and pre-heating apparatus, a supply reservoir at a level below the pumping apparatus, and automatic means to permit all liquid remaining in the system upon cessation of pumping to drain back into the reservoir.

4. In liquid feed systems of the character described, the combination of pumping and pre-heating apparatus, a supply reservoir exterior of the building housing the pumping apparatus, and means automatically operative to return all liquid remaining in the system upon cessation of pumping to the supply reservoir.

5. In liquid feed systems of the character described, the combination of pumping and pre-heating apparatus, an accumulator and controlling devices through which the liquid is continuously passed en route to the point of delivery; a pipe connecting with the discharge sides of the pump, accumulator and controlling devices aforementioned to permit draining of all liquid remaining in the system upon cessation of the pumping; and means to prevent flow through said pipe during normal operation of the system.

6. In liquid feed systems of the character described, the combination of pumping and pre-heating apparatus including a supply reservoir, a number of controlling devices through which the liquid is continuously passed en route to the point of delivery, a pipe connecting with the discharge sides of the pump, pre-heating and controlling devices aforementioned to return any liquid left in the apparatus upon cessation of the pumping to the supply reservoir, and means to prevent flow through said pipe during normal operation of the system.

7. In liquid feed systems of the character described, the combination of pumping apparatus including a supply reservoir, a pre-heater and an accumulator through which the liquid is continuously passed en route to the point of delivery, a pipe connecting the discharge sides of the pump, the preheater and the accumulator to the supply reservoir to permit gravitation of any liquid remaining in the system upon cessation of the pumping back to the supply reservoir, and means interposed in said pipe to prevent flow through the same during normal operation of the system.

In testimony whereof, I have hereunto signed my name at Philadelphia, Pennsylvania, this 8th day of April, 1925.

JAMES D. LALOR.
